UNITED STATES PATENT OFFICE.

GUSTAF E. ANDERSON, OF BROCKTON, MASSACHUSETTS, ASSIGNOR TO THE PEERLESS MACHINERY COMPANY, OF BOSTON, MASSACHUSETTS, A CORPORATION OF MASSACHUSETTS.

FOLDING MACHINE.

Application filed May 26, 1923, Serial No. 641,601. Renewed November 17, 1927.

This invention relates to folding machines and more particularly to a pressing mechanism for use in such machines and is herein shown as embodied in a folding machine adapted for folding a binding around the edge of sheet material.

In the shoe manufacturing industry it has been customary to provide certain shoe parts with a binding of suitable material which is stitched to the right side of the shoe part at the edge thereof, and then, in order to conceal the stitching, turned over in a reverse direction around the edge of the shoe part, the free edge of the binding being pressed into cemented relation with the body portion of said shoe part on the wrong side thereof. The free edge of the binding or the wrong side of the shoe part, or both, are previously coated with cement which is allowed to dry to a tacky condition so that when the work is done the pressing of the free edge of the binding upon the body portion of the shoe part will cause the same to adhere closely thereto. When this work is properly done, the edge of the shoe part presents a neat, attractive and finished appearance. In some shoe parts, however, it has been customary, in order to secure a varied design, to attach a marginal strip of material, differing either in texture or color, or both, to the shoe part at the edge thereof by stitching, or otherwise, said marginal strip projecting to a greater or less extent beyond the edge of the shoe part, and to provide the projecting edge of the marginal strip with a binding similar to that above described. When the marginal strip projects beyond the edge of the shoe part a distance less than the width of the pressing means in the folding machine, difficulty is experienced in applying the binding by means of the machine for the reason that the pressing means extends beyond the width of the marginal strip to a point where a double thickness of material is interposed between the pressing member and the anvil, which, of course, prevents full pressure being applied to the free edge of the binding. Under such circumstances it is impossible to secure good results by the use of a machine and the work has to be done by hand.

The main object of the invention is the provision of a folding machine adapted for work of the foregoing character in which

the pressing means are so constructed that the necessary pressure is applied to the work even though that portion of the work under the pressing means may vary in thickness.

Another object of the invention is the provision of pressing means which is adapted for use in any type of folding machine where those portions of the work operated upon by the pressing means may vary in thickness.

Other objects of the invention will be more specifically described and set forth hereinafter.

My invention contemplates the provision in a folding machine of a pressing mechanism adapted for pressing work of varying thickness, such, for instance, as that hereinbefore described. Preferably, I accomplish this end by providing a pressing member made in two parts, one part having a pressing surface of reduced area adapted to engage the edge of the work where it is of even thickness and operating in the usual manner and the other part having a pressing surface which constitutes an extension of the pressing surface of the first part and being yieldingly mounted to engage thicker portions of the work.

For the purpose of illustration, I have shown one embodiment of my invention applied to a folding machine of the general type shown and described in United States Letters Patent No. 1,294,919, issued to William F. Lautenschlager, February 18, 1919, as adapted for applying cord binding, but it is to be understood that my invention is capable of broad application to folding machines generally whether they be designed for folding the skived edges of sheet material or cord binding.

In the accompanying drawings Figure 1 is an end elevation of a folding machine of the Lautenschlager type having a pressing mechanism constructed and operated in accordance with my invention; Fig. 2 is a bottom plan view of the pressing mechanism looking upwardly in Fig. 1; Fig. 3 is a view in perspective of the pressing mechanism with the various parts disassembled; Fig. 4 is a vertical sectional view of the pressing mechanism operating on work of varying thickness, said view being on an enlarged scale and in a plane transverse to the normal line of feed of the work through the

machine; and Fig. 5 is a view in perspective of the toe portion of a shoe vamp having its throat edge provided with a projecting marginal strip with cord binding to illustrate the character of work for which my invention is designed.

Referring to Fig. 1 of the drawings, which is an end elevation of a folding machine of the general type of the Lautenschlager patent hereinbefore referred to, 10 indicates a lower arm and 12 an upper over-hanging arm, both of these arms carried by a frame not shown. Upon the ends of these two arms are mounted the various instrumentalities 15 for performing the work, the actuating mechanism for imparting the necessary motions to such of said instrumentalities as have motion being carried by the frame and said two arms. In Fig. 1 only such portions of the Lautenschlager machine are shown as are necessary to illustrate the application of a pressing device embodying my invention to that type of machine and the said Lautenschlager patent may be referred to for a full description of all the parts and mechanisms not herein shown.

Upon the lower arm 10 is mounted a work-support 14 having its forward edge bevelled and provided with a stationary plate 15 secured thereto and having a diagonal upturned edge 18 for wiping over or straightening the binding as the work is fed through the machine by a feed foot 20 co-operating with an idler roll 21 mounted upon a screw stud 22. The lower end of the feed-foot 20 is provided with teeth for gripping the material and pressing it against the idler roll during the feeding movement. The feed-foot 20 is formed upon the lower end of a feed-bar 24 which is loosely mounted in a housing 25 carried by the feed-shaft not shown. A split collar 26 is secured to the upper part of the feed-bar 24 by means of a screw 27, this collar being so connected to the lift-shaft 28 that the rocking of the lift-shaft during the operation of the machine reciprocates the feed-bar 24 vertically at the proper times. The rocking of the feed-shaft rocks the housing 25 and imparts to the feed-foot a forward and rearward movement. The result of the operation of the lift-shaft 28 and feed-shaft is a four-motion feed, the feed-foot descending to engage the material, then moving from right to left in Figure 1 away from the operator to feed the material, then lifting to disengage from the material at the end of the feeding movement and then moving backwardly to the initial starting point ready to descend to again grip the material for feeding, this motion being the same as that shown in the said Lautenschlager patent.

For turning the binding over the edge of the material any suitable turning means, such as a plow 30 as shown in the Lauten-

schlager patent may be secured to the work-support by a screw 31.

For guiding the material as it is fed through the machine any suitable guide may be provided and one such is shown comprising a guide-bar 34, having its lower end formed with a guiding edge, which is slidably mounted in bearings 35 and 36 on a bracket 37 which in turn is fastened to the upper arm 12 so that the guide-bar is held in a depending position over the work. As thus mounted the guiding edge of the guide-bar engages the edge of the material around which the binding is to be turned, above the binding. In order that the guide bar may, when necessary, be raised into an inoperative position, and locked therein, a split block 40 is adjustably mounted on the guide-bar 34 and a helical spring 41 encircles the guide-bar abutting at its lower end the split-block 40 and at its upper end the bearing 36. The spring is under compression and therefore holds the guide bar in a downward operative position with the block 40 in engagement with the bearing 35. A handle 42 is fastened in the block 40 whereby the guide-bar 34 may be raised in the bearings compressing the spring 41 and may be locked in an inoperative position by merely turning the block into a recess 43 formed in the adjacent edge of the bracket 37, the front end of the block projecting forwardly for this purpose. The guide bar is returned to operative position by turning the block out of the recess when the spring 41 forces it downwardly.

None of the foregoing construction constitutes any part of my invention, the main parts of the machine being taken from the Lautenschlager patent hereinbefore referred to. The stationary wiping plate is described and claimed in a prior application filed in the United States Patent Office by Lorenz Muther and Frederick S. Glines on July 24, 1922, Serial No. 576,965, and the guiding mechanism is described and claimed in an application filed in the United States Patent Office by Frederick S. Glines, July 29, 1922, Serial No. 578, 289.

The novel features of my invention reside in the pressing mechanism provided for pressing the turned-over edge of the binding down upon the body portion of the material. In the embodiment of the invention shown in the drawings, the pressing mechanism is made in two parts, one in the form of a plate 44 having on its lower edge at one end a pressing member 46 adapted to engage the work and the other part being in the form of a plate 48 having one end 50 bent outwardly and then inwardly in order to partially surround the pressing member 46 on the plate 44 when the two members are assembled together. The lower edge 52 of the end 50 operates as an additional pressing surface. The pressing

member 46 is substantially perpendicular to the plate 44 and may be of any suitable shape, but is preferably rectangular and may, if desired, be provided with corrugations on its pressing surface; said corrugations being transverse to the normal line of feed for the purpose of permitting the free edge of the binding on convex curves to form naturally into pleats under the impact of the pressing member.

The two parts 44 and 48 are mounted on the portion 54 of a screw stud 56, the parts being provided with suitable holes for this purpose 58 and 60 respectively. The screw stud 56 is screwed into a threaded hole 62 in the lower end of a lever 64 which is provided with an integral shaft 66 loosely mounted in a suitable bearing on a lower portion of the upper arm 12. For the purpose of locking the part 44 on the lower portion of the lever 64 in engagement with the face of that lever 68 a pin 70 is set in the face 68 and projects into a hole 72 in the part 44 in relation to the lever 64. When mounted on the screw stud 56 the two parts 44 and 48 are in engagement with each other, the part 48, however, being pivotally movable on the screw stud in relation to the part 44 and to hold the part 48 in downward position, a spring 74 is provided having one end secured in a hole 76 in the part 44 and the other end secured around a hooked portion 77 on the member 48. The spring 74 therefore holds the part 48 in a downward position in relation to the part 44 and a suitable stop 78 is fixed to the part 44 and is adapted to engage a recessed portion 80 in the part 48, thus limiting the downward movement of the part 48. The stop 78 is so placed that when the part 48 is in engagement therewith the pressing surface 52 on that part lies in approximately the same plane as the pressing surface of the pressing member 46. The two parts 44 and 48 of the pressing mechanism therefore move at all times as a unit except when the work underneath the portion 50 of the part 48 is thicker than the work under the pressing member 46 of the part 44, in which case the downward movement of the part 48 will end before the downward movement of the part 44, the tension of the spring 74 then acting upon the part 48 to furnish the adequate pressure for that portion of the work under that part.

Mounted in the lever 64 is a threaded screw 82 held in locked position by a check-nut 84 and provided with a longitudinal hole 86 in its end in which is mounted a spiral spring 88 which bears against a block 90 set in an arm 92 fixedly mounted on the end of the lift shaft 28. Through the medium of these parts the lever 64 is rocked by the oscillation of the lift shaft 28 to raise and lower the pressing mechanism and the machine is so timed that the pressing mechanism is down between the feeding movement and elevated during the feeding movements. To hold the lever 64 in such position that the spiral spring 88 engages a block 90 at all times a spring 94 set in a hollow screw 96 bears against the upper portion of the lever 64. The screw 96 is threaded through an arm 98 constituting a part of the upper arm 12 of the machine. The screw 96 may be turned in the arm 98 in order to adjust the pressure exerted upon the arm 64 by the spring 94. To raise the pressing mechanism at any time when necessary for placing work in the machine or for any other cause, the operator presses the lever 64 against the pressure of the spring 94.

The operation of the machine is as follows, assuming that it has been properly adjusted and the movements of the various parts timed in relation to each other. As stated hereinbefore, this machine is designed with special reference to applying a binding to the edge of a marginal strip secured to the edge of the shoe part. In Figure 5 of the drawings such a part is shown in perspective, comprising the fore-part 100 of a shoe vamp to the throat edge 102 of which is secured by stitching 104 a marginal strip 106, this marginal strip having attached to its right side a binding 108 which is folded in a reverse direction to conceal the stitching around the edge of the marginal strip and pressed down in cemented relation upon the wrong side of the marginal strip. It will be observed that the throat edge 102 of the fore-part 100 of the vamp, which happens to be shown as folded, is somewhat thicker than the marginal strip 106 with the binding 108. In this case the marginal strip projects but a slight distance beyond the edge of the vamp and therefore when operated upon by the machine the pressing device engages both the marginal strip 106 and the edge 102, which necessitates that that portion of the pressing device engaging the double thickness of the edge 102 of the vamp should be resilient in order to permit full pressure to be applied to the binding on the marginal strip.

In presenting work of this character to the machine the binding is previously stitched to the edge of the marginal strip and turned over in a reverse direction by the operator, the free edge of the binding at this point lying in a plane substantially parallel with the work. The work is placed in the machine wrong side uppermost, the feed-foot being raised by pressing the lever 64 against the pressure of the spring 94 to raise the pressing mechanism away from the work support; the part 44 being provided with an extension 110 which engages a cut-away portion on the feed bar 24 to raise the same when and only when the arm 64 is operated by the operator. The starting of the ma-

- chine causes the work to be fed forwardly and during the forward movement of the work the upright oblique edge 18 of the plate 15 catches upon the binding and tends to straighten it out or to wipe it out in a direction away from the work. In this straightened condition the binding engages the plow as the work is fed forward and is turned over by the plow around the edge of 10 the marginal portion 106 and downwardly toward the wrong surface of the marginal portion and in position to be pressed upon that portion when the pressing mechanism descends at the end of the feeding movement. 15 The pressing mechanism remains in pressing engagement with the work during the return of the feed-foot to its initial position at the beginning of the feeding movement so that the pressing mechanism not only serves 20 to press the free edge of the binding into cemented relation with the marginal strip but also serves to hold the work between the feeding movements.

In Figure 4 is shown in detail and on an enlarged scale the operation of the pressing mechanism upon work of this character. The pressing member 46 is shown in engagement with the pressed down free edge of the binding and extends substantially the entire 30 width of the marginal strip, but since that portion of the work under the pressing member 46 is of substantially the same thickness, the pressure exerted by that member is evenly distributed over its entire surface 35 and the binding is pressed into secure cemented engagement with the marginal strip. The part 48, however, which serves as an extension of the pressing surface is shown in engagement with the thicker portion of the 40 work at the edge 102 of the vamp and consequently is shown in a somewhat contracted position with relation to the pressing member 46, the pressure exerted by the pressing surface 52 of the part 50 being due to the 45 spring 74. It so happens, however, in the present instance that this pressure is immaterial since the binding does not extend under the part 50. In some cases, however, it may be necessary that pressure should be 50 imposed beyond the limits of the pressing member 46, in which case the pressure exerted by the spring 74 would accomplish the necessary result.

It will be noticed that as shown in Figure 55 2 of the drawings, the member 50 extends beyond the pressing member 46 toward the operator and is curved inwardly at its end. This is to facilitate folding upon convex curves of small radii, in which case the folded edge of the work is turned in a direction oblique to the normal line of feed and away from the plow.

One advantage of providing pressing means having a portion of the pressing surface resilient is that the non-resilient portion

may be adjusted slightly lower in order to exert full pressure upon the work than would be permitted where the entire pressing face is fixed. At the same time the presence of a resilient portion produces better results 70 in passing over seams in the work for the reason that the resilient portion automatically adjusts itself to varying thicknesses in the work and its presence prevents any dragging of the pressing mechanism upon the 75 work due to seams or thickened portions passing under the pressing mechanism.

Although I have shown my invention in connection with a folding machine adapted for applying binding to the edge of sheet 80 material, it is not to be limited to that particular use, since a pressing device which is provided with a resilient portion is adapted for use on folding machines intended for folding the edges of sheet material either 85 skived or unskived, whenever the thickness of the material being folded or those portions of the work which may come under the pressing mechanism vary in thickness.

What I claim is:—

1. In a folding machine, the combination of means for feeding work comprising sheet material having a projecting marginal strip attached to one side at the edge thereof and a binding attached to the free edge of said marginal strip for folding around the edge of said strip in a reverse direction, means for turning said binding around the edge of said marginal strip and means for pressing the free edge of said binding on the body of said marginal strip; said pressing means comprising a pivotally mounted main member having its longitudinal axis parallel to the normal line of feed and provided at its free end with a laterally extending pressing portion, an auxiliary member loosely mounted on the same pivot point as said main member and in sliding engagement therewith and having its forward end turned around and enclosing the free end of the said pressing portion on said main member, the lower surface of said free end being adapted to serve as an additional pressing surface, a spring for holding said auxiliary member in the lowermost position and a stop carried by said main member for limiting the downward movement of said auxiliary member under the tension of said spring and for normally holding said auxiliary member in such position that the pressing surface lies in the same plane with the the pressing surface on the lateral portion of said main member.

2. In a folding machine, the combination of means for feeding work comprising sheet material having a projecting marginal strip attached to one side at the edge thereof and a binding attached to the free edge of said marginal strip for folding around the edge of said strip in a reverse direction, means for turning said binding around the edge of said

- marginal strip and means for pressing the free edge of said binding on the body of said marginal strip; said pressing means comprising a pivotally mounted main member 5 having its longitudinal axis parallel to the normal line of feed and provided with a laterally extending corrugated pressing surface, a loosely mounted auxiliary member having a pivot point in alignment with the pivot point of said main member and its forward end, partially surrounding said pressing surface on said main member to serve as additional pressing surface, a spring for holding said auxiliary member in the lowermost position while permitting it to yield when engaging thicker portions of the work and a stop carried by said main member for limiting the downward movement of said auxiliary member so that the pressing 10 surface of said auxiliary member lies in the same plane with the pressing surface of said main member.
3. In a folding machine, the combination of means for feeding in a step-by-step manner work comprising sheet material having a projecting marginal strip attached to one side at the edge thereof and a binding attached to the free edge of said marginal strip, means for turning said binding around 15 the edge of said marginal strip and means for pressing the free edge of said binding upon the body of said marginal strip and for holding the work between the feeding movements; said pressing and holding means comprising a pivotally mounted main member 20 having its longitudinal axis parallel to the normal line of feed and provided at its free end with a right-angled laterally extending pressing portion, a loosely mounted auxiliary member having its pivot point 25 in alignment with the pivot point of said main member and having its free end turned around and enclosing the lateral pressing portion on said main member, the lower face of the free end of said auxiliary member serving as an auxiliary pressing surface, said auxiliary member being normally in close engagement with said main member, a spring attached at one end to said main member and at the other end to said auxiliary member for holding said auxiliary member in the lowermost position in relation to said main member and a stop carried by said main member for engaging the lower edge of said auxiliary member to limit its downward 30 movement under the tension of said spring.
- In witness whereof, I hereunto set my hand this twenty-fourth day of May, 1923.

GUSTAF E. ANDERSON.
